UNITED STATES PATENT OFFICE

100,561

DESIGN FOR A COMBINATION MANICURE BOTTLE, CAP, APPLICATOR, AND PENCIL

Edward A. Henske, St. Louis, Mo.

Application April 7, 1936, Serial No. 61,992

Term of patent 14 years

To all whom it may concern:

Be it known that I, Edward A. Henske, a citizen of the United States, residing at St. Louis, in the county of St. Louis and State of Missouri, have invented a new, original, and ornamental Design for a Combination Manicure Bottle, Cap, Applicator, and Pencil, of which the following is a specification, reference being had to the accompanying drawing, forming part thereof.

tion manicure bottle, cap, applicator, and pencil, showing my new design.

Figure 2 is a view in top plan thereof.

The dominant features of my design reside in the portions shown in full lines.

I claim:—

The ornamental design for a combination manicure bottle, cap, applicator, and pencil, as shown and described.

EDWARD A. HENSKE.
